ATTORNEY

UNITED STATES PATENT OFFICE

HARRY AGLOW, OF PHILADELPHIA, PENNSYLVANIA, ASSIGNOR TO GILL GLASS AND FIXTURE COMPANY, A CORPORATION OF DELAWARE

LIGHTING FIXTURE

Application filed March 2, 1929. Serial No. 344,065.

The present invention relates to lighting fixtures and is more particularly directed toward the provision of an improved type of lighting fixture employing glass shades about 5 the lamp bulbs.

There has heretofore been considerable effort made in the design of lighting fixtures to provide the individual light sources with permanent glass shades; with a view to having these shades a part of the ornamental scheme of the fixture design and at the same time provide the desired shade for the light source. These designs, however, have been defective from the aesthetic point of view on 10 account of the difficulty of hiding and concealing the lamp bulb and socket so that they were concealed from observation irrespective of whether the fixture was lighted or not.

The present invention contemplates a fixture design suitable for chandeliers and wall brackets wherein glass shades may be employed and wherein the lamp and socket are both so effectively concealed that they are not visible or noticeable when viewing the 15 hanging fixture.

According to the present invention, the lamp is carried inside the glass shade in such a manner that the entire shade glows when the lamp is lighted and no observable part of the 20 shade is darkened by the lamp socket or on account of shadows.

The present invention also contemplates the design of a fixture for this purpose which is capable of quick and easy assembly and 25 wiring.

The invention also contemplates an arrangement whereby the shades are readily detachable from the metal supporting parts when the lamp bulb is out of the socket. This 30 makes it possible to ship the fixture with very little likelihood of breakage of the glass parts, and also makes it possible to readily remove the glass parts for cleaning. They are held in place by gravity and without the 35 use of any fastening devices.

The accompanying drawings show, for purposes of illustrating the present invention, one of the many possible embodiments in which the invention may take form, it being understood that the drawings are illustra-

tive of the invention rather than limiting the same.

In these drawings:

Figure 1 is a side elevational view through a part of a chandelier, parts being shown in 55 section;

Figure 2 is a top plan view with parts broken away;

Figure 3 is a section on the line 3—3 of Figure 1, showing a form of lamp socket;

Figure 4 is a view taken in the direction of the arrow 4—4 of Figure 1; and

Figure 5 is a perspective view of a ceiling fixture.

When the present invention is employed in chandeliers one may use a single casting forming the body of the chandelier. This may be varied according to the ornamental design which is to be used and it will be understood that the shape of the parts shown 65 in the present drawings is merely illustrative. The chandelier body is indicated in the drawings at 10. It has a central portion 11, radially extending arms 12 and shade supporting and receiving baskets 13, 13. These baskets 70 may be, as here shown, in the form of a ring 14 or may have other shapes and be provided with grille work or other forms of ornamental design according to the style of the fixture.

These shade supporting and receiving baskets, rings or whatever type of structure that may be employed, are each adapted to receive a glass shade. A shade of typical shape is indicated at 15 in the drawings. This shade 75 is adapted to rest in the basket or ring and may protrude below it as shown in the drawings. The shade near its upper part has a side opening 16 of the proper size to receive a lamp socket 17.

Various forms of lamp sockets may be employed, but I prefer to employ a keyless socket with permanently attached leads 18 and 19. The socket is provided with a rearwardly extending mounting bracket 20 85 which may be provided by bending back one of the mounting lugs provided with certain types of sockets now on the market, or a separate brass angle may be employed as indicated in the drawings. The bracket 20 is 90 95 100

apertured to receive a mounting screw 21 as indicated, this screw being threaded into a tapped hole in lug 22 provided in the casting 10.

5 In assembling the fixture in the factory, the sockets are mounted on the body member and such supporting spindles, stems or other devices as the design and fixture style require, are fastened to the body member in the usual manner. The wiring of the fixture is readily accomplished by twisting together the various leads from the sockets and connecting these to the fixture leads. This makes a very economical assembly of fixtures 15 as it eliminates securing of wires to socket terminals and the soldering of a number of joints.

The shades are preferably reentrant at the top as indicated at 24 and are provided with 20 a comparatively large opening 25. This opening is preferably nearly the full diameter of the shade. When it is desired to place the shades in place, it is merely necessary to pass them down by the socket and into the basket where they are supported by gravity. The lamp bulbs 26 may be readily threaded into the lamp socket.

30 The arms 12 which extend between the central portion of the fixture body and the shade receiving baskets or rings are comparatively short. They are preferably of just sufficient length to accommodate the lamp socket and are provided with upwardly extending wings or side members 27 to conceal the lamp 35 socket and hide the opening in the shade. This portion of the fixture body may be considered as channel-shaped in cross-section so as to provide a trough for the lamp socket.

Where the present form of construction is 40 employed in a chandelier of larger spread than the two-light fixture indicated in the drawings, it is of course understood that the center portion may be in the form of a spider or of any other form commonly employed 45 in the center of chandelier plates and the like. When the invention is adapted for use in bracket type fixtures, the back plate will be arranged to support the socket and shade supporting basket so that the lamp bulb may 50 be inserted and concealed.

55 When these fixtures are hung in the ordinary position, the under surface of the fixture body and the outside of the glass shade (together with a tassel or other device indicated at 27) is all that the observer sees. The socket and lamp are effectively concealed by the shape of the fixture body and by the translucent shade. When the lamp is lighted, the entire shade glows and no parts of 60 the shade are shadowed by the socket. At no time when the fixture is hanging is one able to see either the socket or lamp when observed at from ordinary angles. The fixture presents a pleasing appearance and completely shades the light source providing a

soft semi-indirect light of pleasing character.

It is obvious that the invention may be embodied in many forms and constructions, and I wish it to be understood that the particular form shown is but one of the many forms. Various modifications and changes being possible, I do not limit myself in any way with respect thereto.

I claim:

1. In a lighting fixture, a chandelier body having a central portion and narrow radially extending arms each terminating in a shade receiving and supporting basket, a lamp socket mounted on each arm with its axis substantially horizontal and the socket opening toward the corresponding basket, and a translucent glass shade fitted in each basket, the shades being open at the top and having side apertures to receive the lamp sockets and being freely removable from the chandelier body in the absence of lamp bulbs in the sockets without disturbing the sockets, the baskets and shades being spaced from one another so that the sides of the shades are visible from substantially all directions.

2. In a lighting fixture, a chandelier body having a central portion and narrow radially extending arms each terminating in a shade receiving and supporting basket, a lamp socket mounted on each arm with its axis substantially horizontal and the socket opening toward the corresponding basket, the arms having side walls adjacent the sockets and acting to conceal the sockets against observation when the fixture is viewed from underneath, and a translucent glass shade fitted in each basket, the shades being open at the top and having side apertures to receive the lamp sockets and being freely removable from the chandelier body in the absence of lamp bulbs in the sockets without disturbing the sockets, the baskets and shades being spaced from one another so that the sides of the shades are visible from substantially all directions.

3. In a lighting fixture, a chandelier body having a central portion and narrow radially extending arms each terminating in a shade receiving and supporting basket, a lamp socket mounted on each arm with its axis substantially horizontal and the socket opening toward the corresponding basket, and a translucent glass shade fitted in each basket, the shade being open at the top and having side apertures to receive the lamp sockets and being freely removable from the chandelier body in the absence of lamp bulbs in the sockets without disturbing the sockets, the baskets and shades being spaced from one another so that the sides of the shades are visible from substantially all directions, each socket being placed to hold the lamp bulb so that it is concealed in the shade

when not lighted and so that the entire shade glows when the lamp is lighted.

4. In a lighting fixture, a chandelier body having a central portion and narrow radially extending arms each terminating in a shade receiving and supporting basket, a lamp socket mounted on each arm with its axis substantially horizontal and the socket opening toward the corresponding basket, and a translucent glass shade fitted in each basket, the shades being open at the top and having side apertures to receive the lamp sockets and being freely removable from the chandelier body in the absence of lamp bulbs in the sockets without disturbing the sockets, the baskets and shades being spaced from one another so that the sides of the shades are visible from substantially all directions, the sockets having current supply leads permanently connected to the socket contacts and adapted to be secured together to complete the wiring of the fixture.

5. A lighting fixture having an upwardly opening translucent shade apertured at the side, and of generally circular configuration about a vertical axis a shade supporting body member having a ring about the shade to support the same, the shade extending a substantial distance above the ring, a lamp socket secured to the body member and protruding through the aperture in the side of the shade and adapted to carry a lamp bulb within the shade, the shade concealing the bulb.

35 6. A lighting fixture having an upwardly opening translucent shade apertured at the side, and of generally circular configuration about a vertical axis a shade supporting body member having a ring about the shade to support the same, the shade extending a substantial distance above the ring, a lamp socket secured to the body member and protruding through the aperture in the side of the shade and adapted to carry a lamp bulb within the shade, the shade concealing the bulb, the body member having socket concealing side walls which are adjacent the socket and conceal it when the fixture is viewed from underneath, the body member being shaped to cut off substantially none of the light transmitted through the shade above the ring.

7. A lighting fixture comprising a body member, a lamp socket provided with a supporting member having a rearwardly extending apertured foot, a securing device passed through the foot for securing the socket to the body member, a translucent glass shade carried by the body member and having a side opening therein, the shade being spaced from the socket securing device so that the outer end of the socket passes through the side opening in the shade, and 65 a lamp bulb in the socket, the bulb and outer

end of the socket being concealed by the shade.

8. A lighting fixture body having a central portion, short radially extending arms terminating in shade receiving and supporting baskets, an upwardly opening translucent glass shade of generally circular configuration about a vertical axis and carried by each basket, each shade having a lateral opening above the basket, and a socket mounted on each arm and extending toward the opening, the arms adjacent the shades being slightly wider than the sockets and having side walls to conceal the sockets.
